UNITED STATES PATENT OFFICE.

JOHN DOWLING, OF POWELL, WYOMING.

PLOW.

1,206,517.

Specification of Letters Patent. Patented Nov. 28, 1916.

Application filed May 20, 1916. Serial No. 98,735.

To all whom it may concern:

Be it known that I, JOHN DOWLING, a citizen of the United States, and a resident of Powell, in the county of Park and State 5 of Wyoming, have invented a new and Improved Plow, of which the following is a full, clear, and exact description.

My invention relates to a plow having a pair of plowshares disposed back to back 10 on the plow standard and a beam adapted to be turned through an angle to present either of the said plowshares at the front.

More particularly the invention relates to a plow in which the plowshares are separately mounted on the plow standard for vertical sliding movement and means for simultaneously sliding the plowshares in opposite directions to raise either share and depress the other to working position on the 20 standard.

The invention also includes a novel means whereby to secure the plow beam when adjusted in any one of various angular positions to dispose the handle end for the plow- 25 man to follow either in the furrow or on the unbroken land; as well as means to adjust the angular position of the plow handles on the beam.

The invention will be particularly explained in the specific description following.

Reference is to be had to the accompanying drawings forming a part of this specification in which similar reference characters indicate corresponding parts in all the 35 views.

Figure 1 is a side elevation of a plow embodying my invention; Fig. 2 is a fragmentary side elevation, parts being in vertical section and others broken out; Fig. 3 40 is a horizontal section on the line 3—3, Fig. 2; Fig. 4 is a fragmentary side view of the standard showing the opposite side from Figs. 1 and 2; Fig. 5 is an end view of the plow, the beam being in vertical section; Fig. 6 is a horizontal section on the line 45 6—6, Fig. 2; Fig. 7 is a fragmentary plan view showing the means for adjustably mounting the plow handles.

In carrying out my invention in accordance with the illustrated example, a standard, designated generally by the numeral 10 is provided, on which is vertically slideable two separate plowshares, designated generally by the numeral 11. A plow beam 50 12 is mounted to turn relatively to the standard through an angle of at least, approxi-

mately 180° to reverse the position of the beam relatively to the plowshares, and said beam is provided with handles 13.

The standard is provided with vertical 60 guide channels for the plowshares 11. In the illustrated construction one side of the standard consists of a vertical plate 14 and at the opposite side, secured to said plate, at the side edges, are vertical strips 15 together with an intermediate strip 16 spaced from the said strips 15 and in the same plane therewith. Beneath each strip 15 is spacing member 17 is placed of less width, while beneath the intermediate strip 16, 70 spacing members 18 are disposed. The strips 15 and 16 extend laterally at the side edges beyond the respective spacing members, 17, 18, to provide vertical under-cut channels or rabbets between the side strips 75 15 and the intermediate strip 16.

The plowshares 11 are provided with vertical members, T-shaped in cross section having guided movement in the under-cut channels in the standard. In the example 80 shown, vertical members 19 are overlapped by the strips 15, 16, and these are secured to face plates 20 riveted or otherwise secured at one edge as at 21 to the plowshares 11 and bent to extend over the adjacent 85 strips 15 of the standard and to overlap the intermediate strip 16. At the opposite face of the standard 10, each plowshare 11 extends as at 22 to overlap the plate 14 of the standard. Thus, the face plate 20 and 90 the extension 22 receive the side edges of the standard between them. Between the face plate 20 and the members 19, liners or spacing members 23 are disposed and constitute with said members 19, T-shaped 95 slides as clearly seen in Fig. 3.

In order to move the respective plowshares 11 vertically in reverse directions, the sliding members 19 are provided with rack teeth 19a on their opposed edges, and 100 meshing with said rack teeth is a pinion 24 on a transverse shaft 25, which is provided with a crank handle, 26. Thus, by turning the handle, the pinion 24 will raise one plowshare 11 and lower the other to 105 the working position at the lower end of the standard. Any suitable means may be provided for locking the handle 26 against turning after a given adjustment of the plowshares; I have shown for the purpose 110 a pin 26a projecting laterally from the standard, the handle being formed with a

corresponding pin hole to adapt the handle to be sprung into engagement with said pin.

The face plate 20 of each plowshare is secured to the T-shaped slides, consisting of the elements, 19, 23, through the medium of bolts 28. One bolt 28 of each plowshare is utilized to secure the inner end of the brace 27, the outer end of which is suitably fastened as at 28^a to the mold-board.

10 To effect the pivotal connection of the beam 12 with the standard, the said standard is provided with a turntable 29 at its upper end, secured by brackets 30 or equivalent means, and the under side of the plow beam 15 is provided with a wear plate 31 turning on said turntable. On the upper side of the standard may be secured a plate 32. A pivot pin 33 extends through the turntable 29 and through the plow beam centrally 20 through the plates, 31, 32, and is provided with a nut 34. The beam is thus adapted to be turned through an angle to reverse the positions of the handles 13 relatively to the plowshares 11 and dispose the clevis end 12^a 25 of the beam properly with respect to either share.

To secure the beam in adjusted position, a vertical pin 35 or its equivalent, is employed, to receive which the beam is provided with 30 vertical pin holes 36, there being corresponding pin holes 37 in the turntable 29. It will be observed from Figs. 2 and 6 that series of holes 36, 37 are produced in the plate 31 and turntable 29 and out of line radially, the 35 purpose of which is to vary the angle of the beam to dispose the handle end thereof so that the plowman may walk in the furrow or on unbroken land.

The numeral 38 indicates rivets or bolts 40 for securing the plates, 31, 32, to the beam. The numeral 39 indicates a bolt or pin extending vertically through the beam 12, adjacent to the periphery of the turntable 29 and plate 31, said pin having at its lower 45 end a washer or collar 40 projecting laterally to engage beneath the said turntable. The pin or bolt 39 is provided with a pivoted cam lever 41 at its upper end to bind the member 40 against the under side of 50 turntable 29.

The numeral 42 indicates rivets for securing the elements, 15 and 17, and 16 and 18, to the plate 14 of the standard.

In addition to providing the pin 35 and 55 the pin holes for effecting the angular adjustment of the beam 12, I provide means to vary the angles of the handles 13 to the beam; for the purpose a plate 43 is secured to the said beam by bolts, 44, 45. The 60 upwardly extending sides 46 of the plate 43 are flanged as at 47 over the upper sides of

the handles, and additional bolts 48 pass through the said handles and the sides 46. The bolt 44 extends through a curved slot 49 in the plate 43 and receives a wing nut 50. Thus, the handles 13 with the plate 43 may be swung to either side with the bolt 45 as a pivot and secured in the adjusted position by the nut 50, whereby to dispose the handles at a sufficient angle to the plow beam 70 for the plowman to follow the furrow or walk on the unbroken land.

I wish to state in conclusion that although the illustrated example constitutes a practical embodiment of my invention, I do not limit myself strictly to the mechanical details herein illustrated, since manifestly the same can be considerably varied without departure from the spirit of the invention as defined in the appended claims. 75 80

Having thus described my invention I claim as new, and desire to secure by Letters Patent:

1. In a plow of the class described a standard having under-cut vertical channels, separate plowshares disposed in opposite directions at the back and front on said standard, a face plate on each plowshare overlying the standard at one of the side faces thereof, and over said channels, each plowshare at the opposite face of the standard overlapping the latter, slides T-shaped in cross section and rigid with the first-mentioned face plates of the plowshares, said slides being vertically movable in said channels, and means engaging said slides to oppositely move the plowshares. 90 95

2. In a plow of the class described a standard, a plow beam, a turntable on the standard beneath the plow beam, a vertical pivot bolt extending through the plow beam and turntable, the said plow beam and turntable having series of vertical pin holes disposed radially out of alignment, and a pin receivable in the respective pin holes of the 100 105 plow beam and turntable when said pin holes are brought into register.

3. A plow beam, a turntable on the standard beneath the plow beam, a vertical pivot bolt extending through the plow beam and 110 turntable, the said plow beam and turntable having series of vertical pin holes disposed radially out of alignment, and a pin receivable in the respective pin holes of the plow beam and turntable when said pin holes are 115 brought into register; together with a vertical pin extending through the plow beam at the periphery of the turntable and having a laterally bent member adapted to engage beneath said turntable.

JOHN DOWLING.
